TEXTILE MACHINE ATTACHMENT

Jacob V. Polcha, Scranton, Pa.

Application November 30, 1935, Serial No. 52,411
Renewed July 14, 1936

4 Claims. (Cl. 28—50)

This invention appertains to new and useful improvements in stop mechanism for textile machines.

The principal object of the present invention is to provide a stop mechanism wherein a separator is provided for the drop wires so that the drop wires will be capable of functioning independently of each other without likelihood of any binding action between the same.

10 Another important object of the invention is to provide means for preventing sticking of the drop wires by including a member for exerting force against the drop wires when the thread of a particular wire becomes broken.

15 Other important objects and advantages of the invention will become apparent to the reader of the following specification.

In the drawings:

Figure 1 represents a fragmentary front elevational view of the improved structure.

Figure 2 is a fragmentary vertical sectional view taken substantially on the line 2—2 of Figure 1.

Figure 3 is a top plan view of a section of the drop wire separator.

25 Figure 4 is a longitudinal sectional view of the separator.

Figure 5 represents a perspective view of one of the separator units.

Figure 6 is an elevational view partly in section 30 of the improved backing means for the drop wires.

Referring to the drawings wherein like numerals designate like parts, it can be seen that numeral 5 represents the frame of the organized mechanism and numeral 6 represent depending arms for supporting rockers denoted by numeral 7. These rockers 7 are mounted on an elongated rod 8. Each of these rockers 7 has its upstanding portion secured to a corresponding drop wire 9, which extends upwardly, obliquely as at 10 and then backwardly as at 11 for attachment to the thread hook 12, which receives the thread 13.

The separator complementary to the drop wires is generally referred to by numeral 14 and consists of the base plate 15 having its longitudinal edge portions bent upwardly and inwardly as at 16 to provide a slideway for receiving the base portions of the L-shaped or angle members 17, the upstanding portions of which are apertured 50 as at 18 to receive the rod 8, which rod also extends through the rockers 7 of the stop mechanism. Thus it can be seen, as in Figure 1, that each of the rockers 7 and its corresponding drop wire 9 is separated from the adjacent unit.

55 The means for preventing sticking and failure

of the drop wires to drop when a thread breaks, consists of the elongated rod 19, having its end portions disposed laterally as at 20 in the same direction and then inwardly as at 21 and then outwardly in parallel relation as at 22 to terminate in laterally disposed pintles 23 which can engage into openings in the arm portions 6. Thus a bail is formed, on the straight portion or rod portion 9 of which a plurality of individually rotatable tubular sections 24 are disposed. The 10 openings through these tubular members 24 are substantially larger in diameter than the diameter of the rod 19 so that as a matter of fact they are quite loose and when the drop wires engage against the same as in Figure 2 with the hooks 12 15 engaging the threads 13, the tubular sections 24 are urged against their tendency to gravitate and centralize to the offset position as shown. However, when one of the threads 13 breaks, the tendency of the corresponding tubular sections 24 to 20 gravitate and centralize itself on the rod 19 results in a movement of the drop wire 9 which is sufficient to cause it to detach itself from the corresponding tube 24 and result in the actuation of the rocker 7. This is highly desirable because 25 frequently the backing wire (for which the rod 19 is substituted) becomes sticky and the drop wires adhere thereto.

While the foregoing specification sets forth the invention in specific terms, it is to be understood that numerous changes in the shape, size and materials may be resorted to without departing from the spirit or scope of the invention as claimed hereinafter.

Having thus described the invention, what is 35 claimed as new is:

1. In a textile mechanism, a drop wire assembly including a plurality of drop wires each including a thread engaging hook and a stop mechanism rocker, a backing wire for the drop wire, said 40 backing wire being provided with a plurality of loosely disposed tubular sections thereon against which the drop wires engage.

2. In a textile mechanism, a drop wire assembly including a plurality of drop wires each including a thread engaging hook and a stop mechanism rocker, a backing wire for the drop wire, said 45 backing wire being provided with a plurality of loosely disposed tubular sections thereon against which the drop wires engage, to hold the said tubular section in laterally offset position when the hooks thereof are engaged with the threads.

3. In an organized mechanism for the purpose described and in combination, a plurality of drop wires arranged side by side, side by side rockers 50

- each in connection with the drop wire, separating members disposed between the rockers and adapted to prevent binding or sticking of the drop wires so that each is free to fall independently of the others, a crosswire rod disposed back of and at right angles to the drop wires, and tubular sections arranged end to end and freely movable on said crosswise rod and engaging the back of the drop wires.
- 10 4. In an organized mechanism for the purpose described and in combination, a plurality of drop wires arranged side by side, side by side rockers

each in connection with one drop wire and having registered apertures, spaced upstanding members resting between the rockers and having apertures registered with those of the rockers and also having angularly disposed portions, a rod extending through said apertures of the rockers and upstanding members, and a base plate having turned longitudinal flanges receiving between them the said angularly disposed portions of the upright members whereby said members are held 10 in the base plate. 5
